CARBURETORS

Alfred Ernest Lauder, Vancouver, British Columbia,
Canada

Application September 26, 1952, Serial No. 311,614

7 Claims. (Cl. 261—71)

This invention relates to improvements in carburetors in which fuels of all types such as gasoline, stove oil and other relatively heavy fuel oils, may be used.

This application is a continuation-in-part of my abandoned application Serial Number 616,673 filed September 17, 1945, and my abandoned continuation application Serial Number 718,831 filed December 27, 1946.

An object of the present invention is the provision of a carburetor in which relatively heavy fuels may be rapidly and efficiently atomized into an extremely fine vapour.

Another object is the provision of a carburetor in which the flow of air is stream-lined in order to reduce turbulence to a minimum so that the minute particles of atomized fuel introduced to said air flow mingle with the air and retain their finely divided state.

Attempts have been made to break up liquid fuel in carburetors by dispersing said fuel from a rotating body in a mixing chamber. These have not been very successful owing to the fact that in all these devices the air in the mixing chamber was in a highly turbulent state. This resulted in the minute particles of fuel being subjected to an intensive bombardment, that is, they were thrown together and against the walls of the chamber, resulting in the fuel being partially reduced to a liquid state, thereby defeating the purpose of the atomizing device. Furthermore, the rotating bodies themselves were unable completely to atomize heavy fuels.

In one form of this invention, fuel is discharged into a spinning cup at the bottom thereof, and this fuel is preferably rotating around the axis of the cup at the same speed as the latter at the moment of discharge. The fuel forms a layer over the surface of the cup which thins out towards its rim. Centrifugal force causes this thinning out resulting in a greater percentage of the fuel being in direct contact with the cup surface and as the latter is moving faster towards its rim, the speed of the fuel will not be diminished by its inertia. Thus, the fuel is discharged from the rim of the cup in an extremely finely divided state.

Another feature of this invention is the fact that the flow of air is streamlined to reduce turbulence to a minimum both before and after the atomized fuel is added to it. This streamlined flow of air is necessary so that the minute particles of fuel will not be subjected to undue churning, swirling, or impact with each other or with the walls of the chamber in which the mixing takes place.

It is well known in aerodynamics that all surfaces have a layer of air in contact with them and that this layer is not easily broken or removed. According to this, each minute particle of fuel has a coating of air which separates it from all other particles. If the particles are subjected to shock or impact by bumping each other or the walls of the mixing chamber, the film of air about some of the particles is ruptured, allowing the particles to coalesce either in the air or upon the chamber walls. This results in solid fuel being directed into the engine where it is of no use whatsoever. This is a waste of

2

fuel and it even results in crankcase dilution and carbon formation.

The streamlined flow of air is directed towards the outlet of the mixing chamber and the latter is so designed that the fuel particles are not subjected to shock or impact.

In the accompanying drawings, Figure 1 is a vertical section through the carburetor, Figure 2 is a reduced plan view thereof, Figure 3 is a reduced plan view of the mixing chamber with its cover removed and certain parts broken away, Figure 4 is a reduced section taken substantially on the line 4—4 of Figure 1,

Figure 5 is an enlarged fragmentary vertical section through an alternative form of the invention, and

Figure 6 is a fragmentary view taken along the line 6—6 of Figure 5.

Referring to Figures 1 to 4 of the drawings, 10 is a bowl-shaped mixing chamber, the walls of which gently curve inwardly from its upper edge and then in the opposite direction down to a central outlet 11 which is adapted to be connected to the intake manifold of an internal combustion engine, not shown. The mixing chamber has a cover 12 in the form of a truncated cone secured thereto in any suitable manner, such as by bolts 13. A substantially cone-shaped grid or plate 14 is mounted on the mixing chamber and spaced below its cover to form an air chamber 15 which converges towards its periphery. The cover 12 is open at its top and is formed with a vertical cylindrical collar 16 closed at its upper end and having a plurality of spaced inlet openings 17 formed therein. A choke ring 18 may be provided. This ring slidably fits on the collar 16 and has a plurality of openings 19 formed therein which correspond to the openings 17 and are adapted to be moved into and out of registry therewith by means of a wire control cable 20.

The conical grid or plate 14 is formed with a blank arm 25 at the apex and has a plurality of passages 26 extending therethrough between said blank area and the wall of the mixing chamber. Each of these passages is preferably longer than its diameter and as the latter must not be too small, this is accomplished by using a relatively thick plate, as shown, or by forming said plate with a boss at each passage. The grid or plate also is formed with a central depending boss 27 having a vertical bore 28 extending therethrough in which a thrust bearing 29 is positioned for rotatably supporting a vertical hollow shaft 30 extending through said bore and through a bushing 31 in the closed end of the collar 16.

A conical atomizing cup 34 is fixedly mounted on the lower end of the shaft 30 in the mixing chamber 10 beneath the blank area of the plate 14. The wall of the cup extends upwardly from the base at a steep angle and tapers in cross section at its periphery to a fine rim 35, see Figure 1. An annular rim 36 projects downwardly from the plate 14 and terminates immediately above the rim 35 of the atomizing cup, leaving a narrow gap 37 therebetween. The shaft 30 has a plurality of radial outlets 40 at its lower end just above the bottom of the cup. Each of these outlets is preferably longer than its diameter and for this purpose, the shaft may be formed with an enlargement 41 at its lower end.

The shaft 30 may be rotated in any desired manner. One very efficient way of doing this is by means of an impeller disc 44 having blades 45 at its periphery, said disc being fixed to the shaft within the collar 16 just below the openings 17 thereof. The diameter of the disc is just a little less than the inner diameter of the collar so that when an area of low pressure is formed in the mixing chamber 10 by the suction of the engine, air is drawn in through the openings 17 and must pass through the

blades 45 to rotate the disc 44 and the shaft 30. This air, which is in a turbulent state in the air chamber 15, passes through the passage 26 of the grid or plate 14 into the mixing chamber. The passages are long enough to straighten out the air so that its flow through the mixing chamber is stream-lined.

The passages 26 are very close together, and when air passes through them at a fairly high velocity, it emerges therefrom in a multiplicity of very fine streams. At a certain distance from the plate each stream tends to spread out in a cone, but the mixing chamber converges gradually towards the central outlet 11. This increases the speed of and compacts the air so that it cannot follow its natural tendency to spread out. In other words, the plate streamlines the air and the mixing chamber substantially keeps it in that form.

Liquid fuel is supplied to the bore of the hollow shaft 30 in any suitable manner. A float chamber 50 is mounted on top of the collar 16 and has a core 51 centrally thereof through which the shaft 30 extends. The shaft terminates at the top of the float chamber and the bore thereof communicates with a passage 52 formed in the cover 53 of the chamber, said passage being controlled by a needle valve 54 adjustably mounted in said cover. A passage 55 which extends through the bottom of the float chamber, the core 51 and the cover 53, communicates at one end with the passage 52 and at its opposite end with the interior of the chamber at 56. A float 57 controls the flow of fuel from a tank (not shown) into the chamber 50 in the usual manner.

In use, fuel passes from the float chamber 50 through the passages 55 and 52, down through the bore of the shaft 30 and out through the outlets 40 into the atomizing cup 34. The low pressure area in the mixing chamber 10 induces this movement. As previously described, the shaft and cup are rotated at high speed. As the outlets 40 are turning at the same speed as the cup, the fuel issuing into the latter is moving around the shaft axis at the same speed. The reason for this is that the elongated outlets act as impellers and give the fuel its initial acceleration. The fuel forms a thin layer over the surface of the cup and centrifugal force causes it to thin out as it moves towards the rim 35. The specific gravity of the heavier fuels aids the action. Thus a relatively large percentage of the fuel is in direct contact with the cup surface and as this surface is moving faster towards its rim, the speed of the fuel is not diminished by its inertia, and in fact, it is actually increasing. The fuel is discharged from the rim of the cup in a very finely divided state.

The angle of the surface of the grid or plate 14 is such that the air passing through the passages 26 is directed towards the outlet 11. The atomized fuel is discharged into the stream-lined flow of air at right angles to the movement thereof. The fuel from the cup does not strike the wall of the mixing chamber because it would have to traverse the entire body of fast-moving air between the point it left the cup rim and said wall. The minute fuel particles, therefore, do not strike the wall and there is no reason for them to bump each other as the air flow is stream-lined. The curved shape of the wall of the mixing chamber directs the fuel-air mixture to the chamber outlet in a smooth and even manner.

The ring 18 may be rotated to choke the engine on starting. The openings 17 and 19 are normally in registry so that there is a free flow of air therethrough. These holes 30 are capable of supplying more air than would ever be required by an engine. When it is desired to choke the engine, the ring 18 is rotated to move the openings 19 relative to the openings 17 in order to reduce the amount of air entering the device. The fuel-air ratio will, of course, be changed at this time.

Better results would be obtained in stream-lining the flow of air if one or more very fine conical screens were

substituted for the plate 14. If more than one screen were used, one would be superimposed upon the other. However, as it is necessary to provide a rigid bearing for the lower end of the shaft 30, a substantially conical plate 65 may be used, see Figures 5 and 6. This plate is formed with a plurality of relatively large holes 66 extending therethrough. As the surface of the plate is inclined, these holes are directed towards the outlet 11 of the mixing chamber 10. One or more layers of very fine wire screen or gauze extend over either or both surfaces of the plate. In this example, layers 68 and 69 of screening overlie the upper and lower surfaces of the plate. Actually, the plate 66 merely serves as a webbing to support the screens and to provide a support for the bearing at the lower end of shaft 30. The total area of the openings of the screens over the holes of the plate must be sufficient to supply more air than the engine would ever need. These holes are so disposed in a staggered manner that there will always be a flow of air over the entire inner surface of the mixing chamber.

It is well known that turbulence produced by a very fine screen or gauze dies out so rapidly that it is unimportant, as a result of which it is possible to use the damping action of the screen or gauze to reduce the turbulence which may be present in a stream of air. Fine screens are used for reducing turbulence in air tunnels which are employed for testing purposes. In these tunnels, the screen is usually followed by a contraction of the air stream to increase the mean speed thereof and so decrease the percentage value of the turbulence. In the present case, the screens in the holes 66 of plate 65 reduce the turbulence of the air or stream-line it, and the mixing chamber 10 contracts the air stream to increase the speed thereof. The atomized fuel is supplied to this air in the manner described above.

It is, however, to be understood that there may be other ways of supplying atomized fuel to the streamline flow of air. The stream-lining of the air flow reduces and prevents the particles of fuel from coalescing, and the described apparatus for supplying the atomized fuel thereto is presently considered to be preferred for this purpose.

What I claim as my invention is:

1. In a carburetor, a mixing chamber, a plate in and extending the full width of said chamber having a plurality of passages therein extending in the same direction, means for supplying air to the chamber through the plate, the passages of said plate stream-lining the flow of all air entering the chamber, a vertical hollow and rotatably mounted shaft projecting into the chamber beneath the plate, means for rotating the shaft, and a conical cup mounted on the lower end of the shaft, said shaft having a plurality of radial outlets therein adjacent the bottom of the cup through which fuel may pass from the shaft interior into the cup.

2. In a carburetor, a mixing chamber, a plate in and extending the full width of said chamber having a plurality of passages therein extending in the same direction, each of said passages being longer than its diameter, means for supplying air to the chamber through the plate, the passages of said plate stream-lining the flow of all air entering the chamber, a vertical hollow and rotatably mounted shaft projecting into the chamber beneath the plate, means for rotating the shaft, and a conical cup mounted on the lower end of the shaft, said shaft having a plurality of radial outlets therein adjacent the bottom of the cup through which fuel may pass from the shaft interior into the cup, and each of said outlets being longer than its diameter.

3. A carburetor comprising a bowl-shaped mixing chamber having a central outlet in the bottom thereof, a hollow vertical shaft extending down into the chamber, a conical atomizing cup fixed on the lower end of the shaft, said shaft having a plurality of radial outlets therein at the bottom of the cup, means for rotating the shaft and the cup, means for supplying fuel to the bore of the shaft,

a conical plate extending across the chamber above the cup, said plate having a plurality of passages therethrough beyond the rim of the cup, each of said passages being longer than its diameter, and means for directing air through said passages past the cup towards the chamber outlet.

4. A carburetor comprising a hollow body divided by an apertured wall to define an air receiving chamber and a mixing chamber, said air receiving chamber having a controlled air inlet and said mixing chamber having a gas outlet remote from the apertured wall, a rotatably mounted open cup concentric with the apertured wall, means for admitting liquid fuel into the cup, means for rotating said cup to disperse the fuel radially therefrom, a float chamber mounted upon the hollow body, said float chamber having a needle valve concentric with the cup, said cup being mounted upon a hollow shaft through which liquid fuel is delivered from the float chamber to said cup, said apertured wall having a depending rim aligned with the periphery of the cup and spaced therefrom to define a narrow annular space through which the fuel from the cup is dispersed across the apertured wall.

5. A carburetor comprising a bowl-shaped mixing chamber having a central outlet in the bottom thereof, a hollow vertical shaft extending down into the chamber, a conical atomizing cup fixed on the lower end of the shaft, said shaft having a plurality of radial outlets therein at the bottom of the cup; means for rotating the shaft and cup comprising an impeller disc mounted on the shaft above the cup, said disc having blades at its periphery through which the air directed through the mixing chamber passes to rotate said disc; means for supplying fuel to the bore of the shaft, and means for directing a flow of air past the cup towards the chamber outlet.

6. A carburetor comprising a bowl-shaped mixing chamber having a central outlet in the bottom thereof, a hollow vertical shaft extending down into the chamber, a conical atomizing cup fixed on the lower end of the shaft, said shaft having a plurality of radial outlets therein at the bottom of the cup, means for rotating the shaft

and the cup; means for supplying fuel to the bore of the shaft comprising a float chamber mounted on top of the mixing chamber, said float chamber having a passage communicating at one end with its interior and at the other end with the bore of the shaft, a needle valve in said passage for controlling the latter, and valve-controlled means for admitting fuel to the float chamber; and means for directing a flow of air past the cup towards the chamber outlet.

7. In a carburetor, a mixing chamber, screening means extending the full width of the chamber, means for supplying air to the chamber through the screen, said screening means stream-lining the flow of all air entering the chamber, a vertical hollow and rotatably mounted shaft projecting into the chamber beneath the screening means, means for rotating the shaft, and a conical cup mounted on the lower end of the shaft, said shaft having a plurality of radial outlets therein adjacent the bottom of the cup through which fuel may pass from the shaft interior into the cup.
